POWER-ACTUATED SAWMILL CARRIAGE DOGGING APPARATUS

George Elenbaas, Ocean Falls, British Columbia, Canada

Application January 22, 1953, Serial No. 332,667

11 Claims. (Cl. 143—125)

The present invention relates to improvements in sawmill dogs and more particularly to the clamping mechanism therefor.

It is an object of the present invention to provide a new and improved dogging mechanism enabling an elongated range of travel for the tong arms thereof.

It is a further object of the invention to provide a dogging mechanism having a favorable mechanical advantage in the transfer of the force of the power mechanism to the clamping points of the tong arms.

It is a still further object of the invention to provide a dogging mechanism that is economical in respect to the power consumption thereof.

Another object is to provide a dogging mechanism that continually exerts the maximum clamping force while in operation and consequently automatically maintains the hold of the tong arms on the log or timber cant.

Still another object of the invention is to provide a clamping mechanism for the tong arms including pneumatic or hydraulically operated motors wherein torsional and bending stresses are not exerted on the cylinders and piston rods of said motors.

It is a further object to provide an improved sawmill dog which has advantages over those constructed heretofore in respect to ease and economy of manufacture, ease and simplicity of operation and flexibility of operation.

In accordance with the illustrated embodiment of my invention I have provided in combination with a sawmill carriage knee a pair of elongated tong members pivotally mounted intermediate their ends on a horizontally reciprocable cross-head located rearwardly of the knee. A vertical guideway is arranged adjacent the knee, the upper and lower tongs each having means to coact with the guideway whereby the tongs are constrained to follow the guideway in a vertical plane perpendicular to the face of the knee.

Mounted on each of the tongs is a fluid pressure motor having a piston reciprocably movable longitudinally of the tong. Connected to the pistons and running over sheaves rotatably mounted on the tongs between the motors and the log-engaging ends is a flexible element whereby, upon movement of the pistons of the respective motors rearwardly of the tongs, the forward, log-engaging ends thereof will be drawn together. A second flexible element is arranged at the rearward ends of the tong members, one end being secured to the piston of the motor of the upper tong and passing over a sheave on the rearward end thereof and the other end being secured to the rearward end of the lower tong, whereby upon movement of the piston of the motor on the upper tong toward the forward end thereof the forward ends of the tongs will be drawn apart.

Other objects and advantages of the present invention will be more readily ascertained from inspection of the following specification taken in connection with the accompanying drawing wherein like numerals refer to like parts throughout, while the features of novelty will be more distinctly pointed out in the appended claims.

In the drawing,

Fig. 1 is a side elevation of a portion of a sawmill carriage equipped with the present invention;

Fig. 2 is a fragmentary top plan view showing the manner in which the flexible elements are coupled to the motor mounted on the upper tong; and

Fig. 3 is a sectional view along line 3—3 of Fig. 1.

The invention herein disclosed is shown associated with a sawmill carriage knee 10 mounted on a carriage head

2

block 11. The knee 10 may be adjustably mounted in the conventional manner, the devices for obtaining such adjustment forming no part of the present invention. Pivotally mounted on a cross-head 12 which is slidably mounted on the knee frame in a manner to be subsequently explained is an upper tong arm or member 13 and a lower tong arm or member 14.

Tong members 13, 14 are restrained to movement in a vertical plane perpendicular to the face of a knee by a connection to the guideway 19 formed with a substantially vertical lower section and an upper section curving rearwardly at an arc, the center of which is approximately the pivot point of the upper tong member 13 in its most usual position. The guideway 19 is of U-shaped cross-section and is provided with a longitudinally extending slot 20 in the web thereof in which are slidably engaged the guide pins 21, 22 pivotally affixed to upper tong guide shoe 23 and lower tong guide shoe 24, respectively. The guide pins 21, 22 are each provided with an enlarged head 25 forming shoulders to engage the surfaces of the guideway web on either side of the slot 20 whereby the guide shoes 23, 24 are constrained to follow the path of the slot. The side channels of the guideway may be braced at suitable intervals by sleeves 30 welded at their ends to the opposite side channels and through which pass the bolts 31.

The forward part of each of the tong members 13, 14 comprises a cylindrical tong holder 27, 28, respectively, each of which is slidably engaged in a tong holder guide bushing 29 pivotally affixed to the respective guide shoes 23, 24 by suitable means, herein shown as the guide pins 21, 22. A back board dog 33 may be affixed to the upper guide shoe 23, the purpose of which is well known. The tong holders extend forwardly of the face of the knee and have removably affixed at their forward ends by suitable means, the work gripping tong elements 32.

The rearward portion of each of the tong members 13, 14 comprises a frame assembly 35, 36, respectively, to which the tong holders 27, 28 are secured. The frame assemblies 35, 36 are substantially identical and comprise a pair of substantially parallel side plates 37, 38, the side plates of the upper frame assembly 35 being tied together at their opposite ends by sprocket bushings 39, 42 secured thereto as by welding, the side plates of the bottom frame assembly 38 being tied together in like manner at their forward ends by the sprocket bushing (not shown) in which the sprocket shaft 63 is journaled and at their rearward ends by an end plate 41 secured thereto by welding or other conventional means. The upper and lower tong members are pivotally supported intermediate their ends in a vertically spaced relation to one another at a point substantially rearwardly of the face of the knee. As shown, the upper and lower frame assemblies are pivotally mounted on cross-head 12 by upper and lower pivot shafts 45, 46 suitably supported on the cross-head and suitably journaled in bushings arranged between the side plates 37, 38.

The motor 15 is preferably a reversible motor having a first fixed element and a second element reciprocably movable longitudinally of the upper tong member 13. As shown, motor 15 is a double acting, fluid pressure motor having a cylinder 50 affixed to the upper frame assembly 35 by cylinder supporting frame 51, the bore of the cylinder being longitudinally aligned with the upper tong member 13 and containing a conventional piston (not shown) attached to the extending piston rod 52, to the outer end of which is secured the chain clamp 53. Suitable fluid inlets (not shown) are provided at either end of the cylinder 50.

The motor 16 may be a single acting motor having a first fixed element and a second element movable upon actuation of the motor in a longitudinal direction rearwardly of the lower tong member 14. As shown, the motor 16 may comprise a single acting, fluid pressure motor having a cylinder 54 affixed to the lower dog assembly 36 by a frame 55, the bore of the cylinder being longitudinally aligned with the lower tong member 14. A conventional piston (not shown) is provided in the cylinder and is attached to the extending piston rod 56, to the outer end of which is secured the chain clamp 57.

A suitable fluid inlet (not shown) is provided at the rod end of the cylinder. The control means for the motors 15, 16 may be of conventional types and form no part of the present invention.

Closing means are provided coacting between points spaced near the forward ends of the upper and lower tongs 13, 14 operable to draw the forward ends together. The closing means include a first flexible element connected at its ends to the pistons of the motors and passing over a first sheave rotatably mounted on the upper tong member 13 at a point intermediate the face of the knee and the upper motor 15, and a second sheave rotatably mounted on the lower tong member 14 at a point intermediate the face of the knee and the lower motor 16 and substantially vertically below the first sheave of the upper tong member. As shown in the drawing in Fig. 2, secured to the chain clamps 53, 57 are the opposite ends of the pair of closing chains 17. Means are provided on the upper and lower tong members cooperative with the closing chains 17 to cause them to have a substantially vertical run between the members at a point near the forward ends of the tongs and runs from the vertical run to each of the chain clamps in a direction substantially aligned with the direction of movement of the pistons. Mounted on the opposite ends of a pivot shaft 60 rotatably journaled in sprocket bushing 39 in the forward end of the upper dog assembly is a pair of sprockets 61. Similarly, a pair of sprockets 62 is mounted on the pivot shaft 63 rotatably journaled in the sprocket bushing in the forward end of the lower dog assembly 36 and substantially vertically below the sprockets 61. As may be seen, the sprockets 61, 63 cooperatively engage the closing chains 17 to provide the aforementioned means and form the desired chain runs.

Opening means are provided to draw the forward ends apart, the opening means including means coacting between points spaced near the rearward ends of the upper and lower tongs 13, 14 operable to draw the rearward ends together and thus the forward ends apart. The opening means include a second flexible element connected at one of its ends to the piston of upper motor 15 and passing over a third sheave rotatably mounted at the rearward end of the upper tong member to the rearward end of the lower tong member 14 to which the other end thereof is connected. As shown, secured to chain clamp 53 is one end of each of the pair of opening chains 18, the other ends of each chain being secured by a suitable clamp 65 at the rearward end of the lower dog assembly 36. Means in the form of sprockets 66 mounted in a pivot shaft 67 rotatably journaled in the sprocket bushing 42 are provided cooperative with the opening chains 18 to cause them to have a first run leading from the rearward end of the lower tong member 14 to the rearward end of the upper tong member 13 and a second run from said first run to the chain clamp 53 substantially aligned with the direction of movement thereof.

The cross-head 12 is slidably mounted on the cross-head guide bars 70 in a conventional manner and is adapted to be reciprocally moved thereon by a suitable motor such as the double-acting, fluid pressure motor 71, the cylinder of which is secured to the frame of the knee in a conventional manner, the piston of the motor being connected to the cross-head by the piston rod 72.

The operation of the device should be readily apparent. To draw the forward, log-engaging ends of the tong members 13, 14 together, actuating fluid is admitted to the rod ends of each of the motors 15 and 16 whereupon the pistons thereof will be urged toward the rearward end of the respective tong members drawing the closing chains 17 over the sprockets and decreasing the length of the bight thereof whereby the forward ends of the tong members will be drawn together. Since the sprockets 61, 62 are located close to the log-engaging tong elements 32, a very favorable mechanical advantage is realized as to the amount of force exerted by the long ends as compared to the power consumption of the motors. Thus motors of relatively small bore may be utilized which require relatively small amounts of compressed air or fluid and consequently have a relatively low amount of power consumption as compared with other types of dogging mechanisms. So long as actuating fluid is applied under pressure to the motors, the tong members will be urged together and the

clamping force will be applied to the log-engaging tong elements 32. Thus the hold on the log or timber cant engaged on the knee will be held firm and any "give" in the wood will be taken up automatically.

To release the grip of the tong elements 32 on a log and draw the forward ends of the tong members apart, the application of fluid under pressure to the motor 16 and the forward end of the motor 15 is terminated and pressure fluid supplied instead to the rearward end of motor 15 whereby the piston thereof will be urged toward the forward end of the upper tong member 13. This causes the chains 18 to be drawn over the sprockets 66 at the rearward end of the upper tong member so that the rearward ends of the upper and lower tong members are drawn together and the forward ends thereof are drawn apart.

Horizontal movement of the cross-head 12 and consequently the tong members 13, 14 is attained by actuation of the cross-head motor 71. As before stated, the tong holders 27, 28 are slidably engaged in the pivotally mounted guide bushings 29, 30 so they may freely move reciprocally in respect to the face of the knee.

In the illustrated arrangement of the motors 15, 16 and chains 17, 18 it may be observed that cylinder bodies 25 and piston rods are never subjected to any bending or torsional stresses at any phase of the operation. Consequently it is possible to utilize members of relatively slight structural weight and the piston rod glands are subjected to relatively slight wear.

It should be apparent that a flexible element such as a cable could be utilized in place of chains 17, 18 in which case the sprockets 61, 62 and 66 would be replaced with suitable sheaves or pulleys. As used in the claims, therefore, the term "sheave" is to be understood to include sprockets, pulleys and their equivalents. Obviously a single flexible element or multiple elements could be used in place of the pairs of illustrated chains 17 and 18; thus, the singular expressions "sheave" and "flexible element" as used in the claims are to be understood to include the single and multiple forms of the same.

Having illustrated and described a preferred embodiment of the invention, it should be apparent to those skilled in the art that the same permits of modification in arrangement and detail. I claim as my invention all such modifications as come within the true spirit and scope of the appended claims.

I claim:

1. In a sawmill carriage in combination; a knee, a guideway having a vertical lower portion and a rearwardly curving upper portion, upper and lower elongated tong members, means coacting with the tong members and the guideway to constrain the tong members to follow the guideway, the log engaging ends of said tong members extending beyond the face of said knee, means reciprocally movable in a perpendicular direction in respect to the face of said knee for pivotally supporting said tong members intermediate their ends at a point substantially rearwardly of said knee in a vertically spaced relation to one another, a double-acting fluid pressure first motor supported on said upper tong member, a single-acting fluid pressure second motor supported on said lower tong member, each of said motors having a piston movable in the longitudinal direction of said tong members, the piston of said second motor being responsive to admitted fluid to move in a direction rearwardly of said knee, a first flexible element having its ends connected to said pistons, a first sheave rotatably mounted on said upper tong member at a point intermediate the knee and said first motor, a second sheave rotatably mounted on said lower tong member at a point intermediate said knee and said second motor and substantially vertically below said first sheave, said first flexible element coacting with said first and second sheaves whereby, upon operation of said motors to move said pistons away from said knees, said log engaging ends will be drawn together, a second flexible element having one of its ends connected to the piston of said first motor and its other end connected to the rearward end of said lower tong member, a third sheave rotatably mounted at the rearward end of said upper tong member and coacting with said second flexible element whereby upon movement of said piston of said first motor away from the rearward end of said first tong member said log engaging ends will be drawn apart.

2. In a sawmill carriage in combination; a knee, upper and lower elongated tong members, means coacting with the forward ends of said members to constrain their movements in a substantially vertical plane, means pivotally supporting said tong members intermediate their ends at a point substantially rearwardly of said knee in a vertically spaced relation to one another, said means being reciprocally movable in a horizontal direction in respect to said knee, a double-acting fluid pressure first motor supported on said upper tong member, a single-acting fluid pressure second motor supported on said lower tong member, each of said motors having a piston movable in the longitudinal direction of said tong members, the piston of said second motor being responsive to admitted fluid to move in a direction rearwardly of said knee, a first flexible element having its ends connected to said pistons, a first sheave rotatably mounted on said top tong member at a point intermediate said knee and said first motor, a second sheave rotatably mounted on said lower tong member at a point intermediate said knee and said second motor, said first flexible element coacting with said first and second sheaves whereby, upon operation of said motors to move said pistons away from said knees, the forward ends of said tong members will be drawn together, a second flexible element having one of its ends connected to the piston of said first motor and its other end connected to the rearward end of said lower tong member, a third sheave rotatably mounted at the rearward end of said upper tong member and coacting with said second flexible element whereby, upon movement of said piston of said first motor away from the rearward end of said first tong member, the forward ends of said tong members will be drawn apart.

3. In a sawmill carriage in combination; a knee, upper and lower elongated tong members, means pivotally supporting said tong members in a vertically spaced relation intermediate their ends at a point substantially rearwardly of said knee, a fluid pressure first motor supported on said upper tong member, a fluid pressure second motor supported on said lower tong member, each of said motors having a piston movable in the longitudinal direction of said tong members, a first flexible element having its ends connected to said pistons, a first sheave rotatably mounted on said upper tong member at a point intermediate said knee and said first motor, a second sheave rotatably mounted on said lower tong member at a point intermediate said knee and said second motor, said first flexible element coacting with said first and second sheaves whereby, upon operation of said motors to move said pistons away from said knees, the forward ends of said tong members will be drawn together, a second flexible element having one of its ends connected to the piston of said first motor and its other end connected to the rearward end of said lower tong member, a third sheave rotatably mounted at the rearward end of said upper tong member and coacting with said second flexible element whereby, upon movement of said piston of said first motor away from the rearward end of said first tong member, the forward ends of said tong members will be drawn apart.

4. A dogging device for a sawmill carriage knee comprising upper and lower elongated tong members, means pivotally supporting said tong members intermediate their ends in a vertically spaced relation, a double-acting fluid pressure first motor supported on said upper tong member, a single-acting fluid pressure second motor supported on said lower tong member, each of said motors having a piston movable in the longitudinal direction of said tong members, the piston of said second motor being actuated toward the rearward end of said lower tong, a first flexible element having its ends connected to said pistons, a first sheave rotatably mounted on said top tong member at a point intermediate the forward end thereof and said first motor, a second sheave rotatably mounted on said lower tong member at a point intermediate the forward end thereof and said second motor and substantially vertically below said first sheave, said first flexible element coacting with said first and second sheaves whereby, upon operation of said motors to move said pistons toward the rearward end of said tong members, the forward ends of said tong members will be drawn together, a second flexible element having one of its ends connected to the piston of said first motor and its other end connected to the rearward end of said lower tong member, and a third sheave rotatably mounted at the

rearward end of said upper tong member and coacting with said second flexible element whereby, upon movement of said piston of said first motor away from the rearward end of said first tong member, the forward ends of said tong members will be drawn apart.

5. A dogging device for a sawmill carriage knee comprising upper and lower elongated tong members, means pivotally supporting said tong members intermediate their ends in a vertically spaced relation, a first fluid pressure motor supported on said upper tong member, a second fluid pressure motor supported on said lower tong member, each of said motors having a piston movable in the longitudinal direction of said tong members, the piston of said second motor being actuated toward the rearward end of said lower tong member, a first flexible element having its ends connected to said pistons, a first sheave rotatably mounted on said top tong member at a point intermediate the forward end thereof and said first motor, a second sheave rotatably mounted on said lower tong member at a point intermediate the forward end thereof and said second motor, said first element coacting with said first and second sheaves whereby, upon operation of said motors to move said pistons toward the rearward end of said tong members, the forward ends of said tong members will be drawn together, and means operatively arranged between said tong members for drawing said forward ends apart.

6. A dogging device for a sawmill carriage knee comprising upper and lower elongated tong members, means pivotally supporting said tong members in a vertically spaced relation, a first fluid pressure motor supported on said upper tong member, a second fluid pressure motor supported on said lower tong member, each of said motors having a piston movable in the longitudinal direction of said tong members, the piston of said second motor being actuated toward the rearward end of said lower tong member, a first flexible element having its ends connected to said pistons, a first sheave rotatably mounted on said top tong member at a point intermediate the forward end thereof and said first motor, and a second sheave rotatably mounted on said lower tong member at a point intermediate the forward end thereof and said second motor, said first flexible element coacting with said first and second sheaves whereby, upon operation of said motors to move said pistons toward the rearward end of said tong members, the forward ends of said tong members will be drawn together.

7. In a sawmill dogging apparatus, the combination comprising upper and lower elongated tong members pivotally supported in a vertically spaced relation at a point intermediate their ends, a first fluid pressure motor mounted on said upper tong member and having a piston movable longitudinally in respect thereto, a second fluid pressure motor mounted on said lower tong member and having a piston movable longitudinally in respect thereto, a first flexible element having its ends operatively connected to said pistons, means on said upper and lower tong members cooperable with said first flexible element to cause the same to have a substantially vertical run between said upper and lower tong members at a point near the forward ends of said tong members, and runs from said vertical run to said pistons substantially aligned with the direction of movement thereof, a second flexible element having one end connected with said piston of said first motor and the other end connected to the rearward end of said lower tong member, and means on said upper tong member cooperable with said second flexible element to cause the same to have a first run leading from the rearward end of said upper tong member to the rearward end of said lower tong member, and a second run leading from said first run to the piston of said first motor and substantially aligned with the direction of movement thereof.

8. In a sawmill dogging apparatus, the combination comprising upper and lower elongated tong members pivotally supported in a vertically spaced relation, a first fluid pressure motor mounted on said upper tong member and having a piston movable longitudinally in respect thereto, a second fluid pressure motor mounted on said lower tong member and having a piston movable longitudinally in respect thereto, a first flexible element having its ends connected to said pistons, and means on said upper and lower tong members cooperable with said first flexible element to cause the same to have a run between said upper and lower tong members at a point near the forward ends of

said tong members, and runs from said vertical run to said pistons substantially aligned with the direction of movement thereof.

9. A dogging device for sawmill carriage knees comprising upper and lower tong members, means pivotally supporting said tong members intermediate their ends in a vertical spaced relation, a reversible first motor mounted on said upper tong member having a first fixed element and a second element reciprocally movable longitudinally of said upper tong member, a single-acting second motor mounted on said lower tong member having a fixed first element and a second element movable upon actuation in a longitudinal direction toward the rearward end of said second tong member, a first flexible element having its ends connected to said second elements of said motors, a first sheave rotatably mounted on said upper tong member at a point intermediate the forward end thereof and said first motor, a second sheave rotatably mounted on said lower tong member at a point intermediate the forward end thereof and said second motor, a first flexible element having its ends connected to said second elements of said motors and being trained over said first and second sheaves, a third sheave rotatably mounted on the rearward end of said upper tong member, a second flexible element having one of its ends connected to the movable element of said first motor and its other end connected to the rearward end of said lower tong member and being trained over said third sheave, whereby, upon operation of said first and second motors to move said second elements rearwardly of said tong members, the forward ends of said tong members will be drawn together, and, upon operation of said first motor to move the second element thereof forwardly of said first tong member, the forward ends of said tong members will be drawn apart.

10. A dogging device for sawmill carriage knees comprising upper and lower tong members, means pivotally supporting said tong members intermediate their ends in a vertical spaced relation, a reversible first motor mounted in said upper tong member having a first fixed element and a second element reciprocally movable longitudinally of said upper tong member, a second motor mounted on said lower tong member having a fixed first element and a second element movable upon actuation in a direction toward the rearward end of said second tong member, a flexible element having its ends connected to said second elements of said motors, a first sheave rotatably mounted

5 on said upper tong member at a point intermediate the forward end thereof and said first motor, a second sheave rotatably mounted on said lower tong member at a point intermediate the forward end thereof and said second motor, said flexible element being trained over said sheaves whereby, upon actuation of said first and second motors to move said second elements rearwardly of said tong members, the forward ends of said tong members will be drawn together, and means cooperatively arranged with the rearward ends of said tong members operative to draw them together so as to draw the forward ends apart.

10 11. A dogging device for sawmill carriage knees comprising upper and lower tong members, means pivotally supporting said tong members intermediate their ends in a vertical spaced relation, a reversible first motor mounted on said upper tong member having a first fixed element and a second element reciprocally movable longitudinally of said upper tong member, a second motor mounted on said lower tong member having a fixed first element and a second element movable upon actuation in a direction toward the rearward end of said second tong member, a first flexible element having its ends respectively connected to said second elements of said motors, a first sheave rotatably mounted on said upper tong member at a point intermediate the forward end thereof and said first motor, a second sheave rotatably mounted on said lower tong member at a point intermediate the forward end thereof and said second motor, said flexible element being trained over said sheaves whereby, upon operation of said first and second motors to move said second elements rearwardly of said tong members, the forward ends of said tong members will be drawn together.
